VESSEL AND METHOD OF HANDLING SAME

Original Filed Aug. 13, 1943

UNITED STATES PATENT OFFICE
2,406,236

VESSEL AND METHOD OF HANDLING SAME

Alexander M. McDougall, San Francisco, Calif.

Substitute for abandoned application Serial No. 498,546, August 13, 1943. This application August 21, 1944, Serial No. 550,380

4 Claims. (Cl. 114—72)

1

This application is a substitute for abandoned application Serial No. 498,546, filed August 13, 1943, and relates to vessels and method of loading and/or unloading same and has special reference to that type of ship, for example, as illustrated in my U. S. Patent No. 1,913,207 designed especially for carrying vehicles such as railroad cars, automobiles and other forms of rolling stock.

One of the principal objects is to provide novel means for most convenient transfer of such cargo from one deck of the vessel to another in the process of loading or discharging cargo.

The other principal object is that of proper utilization of water ballast in loading and/or unloading the cargo of the vessel, so that these two features combined may result as nearly as possible in the perfection of what might well be termed a self-cargo-handling multi-deck car-ferry.

Other objects and advantages will appear in the further description of the invention.

Referring now to the accompanying drawing forming part of this application and in which like reference characters indicate like parts:

Figure 1 is a broken side elevation of a vessel such as referred to in my former patent supra and illustrative of a vessel having three or more spaced decks available for cargo space.

Figure 2 is a broken plan view of the intermediate or so-called tween deck, and

Figure 3 is an enlarged broken vertical sectional view of the novel combined ramp and bridge and their cooperative relation to the spaced decks.

It is to be understood that the invention here claimed does not involve any specific details of construction but rather the cooperation of the novel elements with a certain type of ship or vessel, and manipulation of the latter in handling of cargo as well as conservation of cargo space within the vessel.

In order to accomplish this it is obvious that any of the vehicles forming the cargo of the vessel that are to be carried upon the tank top deck 1, must, if ramped to or from same be accomplished as nearly as possible to the place of entry to the vessel, which in this instance is at the stern. Thus my illustrating the combined ramp and bridge as far aft as possible and upon either one or both sides of the after cabins and compartments in the center of the vessel for machinery, et cetera.

Furthermore, it is well known to be essential that a watertight bulkhead be maintained just forward of the boiler compartments and inter-

2

mediate of the tank top 1 and tween deck 5, thus the ramp, if well aft as illustrated, will extend about equally fore and aft of such bulkhead. Consequently, I have divided the ramp into a stationary portion 2 within the forward cargo hold above the tank top and the pivotally adjustable portion 3, aft of said bulkhead they being normally when in cooperative position, on the same inclined plane as clearly shown in Figure 3 of the drawing.

Now to provide head room and sufficient clearance for railroad cars, for example, above the stationary portion 2 of the ramp, and still sacrifice as little storage space as possible on the tween deck, I provide a bridge section 4 of the tween deck 5 pivotally mounted as at O and which section, when raised as shown, amply affords the necessary headroom, however, when lowered to the same plane with the tween deck, functions normally either for transportation or storage in conjunction with the other pivoted section 3.

To provide such novel cooperation of a ship's decks for the movement of cargo, I have connected the two otherwise free ends of the section 3 and 4 as by a single line 6 upon either side thereof leading over the necessary bracketed and spaced sheaves 7 and 8 suspended from the next deck 9 above, which may as shown, in Figure 1, be the main deck.

30 In this manner, and when in suspension the two sections obviously counterbalance each other and render the operation of movement of same very simple.

The bridge section 4 may be provided with any suitable means for sustaining the required weight above same, for example, as by laterally extending transverse beams indicated at 10 which may rest within recesses 11 formed therefor in the sides of the opening into which the bridge fits.

35 The ramp section 3 pivoted at 12 is shown as provided with supporting bents 13 and which may be removable if desired and the space otherwise occupied or additional temporary supports may be mounted thereupon to insure the necessary stability for the section 3 when in its raised position and acting as a portion of the deck to which it is pivoted.

40 For convenient movement of this ramp section I have shown a fluid cylinder 15 vertically disposed and provided with a piston rod 16 pivotally attached to the ramp 3 so that any predetermined form of fluid power may be utilized for raising or lowering the section, which obviously, by virtue of the line 6 connections before described, will 45 simultaneously move the bridge section 4.

Now the matter of maintaining the watertight bulkhead just forward of the boiler compartment which is required for safety in such vessel construction, I have provided the arcuately shaped closure 17 depending from and fixed to the free end of the ramp section 3, the same being formed to line up and overlap the adjacent marginal edges of the opening in said bulkhead necessary for the passage of cargo. A permanent portion of the bulkhead is shown at 18 and as forming 10 the after terminus of the fixed portion 2 of the ramp and it is deemed obvious that any form of suitable temporary watertight connection of the closure portion of the ramp may be resorted to, such as greased watertight guides or if desired, bolted for temporary security, as is common in many parts of ship construction.

While the ramping of cars fore and aft on shipboard is old as suggested in my former patent supra as well as others, the instant invention makes use of what is commonly referred to as water ballast space during the loading and/or unloading of such a ship designed especially as a car ferry, or for transporting rolling stock which is susceptible to the force of gravity during its movement.

For this purpose I provide in conjunction with a ship, as here described, auxiliary water space or trimming tanks as at 21 in the fore-peak thereof and at 22 in the stern as indicated in Figures 1 and 2 so that the same may be employed in the longitudinal trimming of the ship to assist in handling of the rolling cargo such as illustrated either when the ramp is being used or not.

It is well known that vessels of this type in which the boilers and engines are well aft, normally remain trimmed by the stern, that is with the stern or heavier after portion much deeper in the water than the bow and what is known as water ballast space is provided the entire length 40 of the ship below the tank top deck 1, such space being divided into suitable compartments fore and aft by certain of the transverse girders below the tank top being formed into watertight bulkheads.

These various compartments are, of course, connected up to the ballast handling pumps and piping system not shown, of the ship and selectively operable for desired navigability thereof. However, in this instance I propose to use such compartments in conjunction with the novel auxiliary compartments just described to expedite loading or unloading of the ship by changing the fore and aft inclination thereof, thus utilizing gravity in the movement of cars therein.

From the foregoing it is apparent that I have devised novel and simple means for assistance in the handling of cargo as well as utilizing the maximum capacity of that type of vessel illustrated

in my former patent supra and my other U. S. Patents Nos. 1,772,612; 1,773,368; and Re. 18,350 with a view of augmenting their successful and economical operation.

Having thus described my invention, what I claim as new and desire to secure by Letters Patent is:

1. In a car-ferry vessel of the type described having a plurality of parallel decks including a tween deck, an adjustable section of said tween deck pivotally attached at its after end in a plane with the normally remaining portion thereof and lowerable to function as a part of a ramp to the deck below same, a fixed section of ramp upon said lower deck and cooperatively engageable with the movable end of said adjustable section, and a second adjustable section of said tween deck directly above said fixed section pivotally attached at its forward end in a plane with said remaining portion whereby to provide ample head-room for objects passing in either direction thereunder when raised and means connecting the free ends of said tween deck sections whereby to insure their operation in unison.

2. A combined bridge and ramp for a car ferry of the type described having a tween deck and a tank top deck comprising, a track carrying portion of said tween deck being hingedly supported at one end to a fixed portion of said tween deck and swingable downwardly from the normal plane thereof and a like portion normally forming a continuation of said tween deck also hingedly supported at its remote terminus from said other portion, and means connecting the free ends of said sections whereby the weight of one counterbalances the weight of the other when moved in opposite directions.

3. In a vehicle ferry of the type described having a tween deck and a lower deck, means for conveying vehicles intermediate of said decks comprising, two cooperatively united swingable sections of said tween deck said union acting as means to insure the free ends of said sections moving in opposite directions when operated and each counterbalancing the weight of the other.

4. An adjustable combined bridge and ramp unit for a car ferry of the type described having an upper and lower deck in the hold thereof comprising, two normally abutting sections of said upper deck being hinged at their remote termini and movable vertically in opposite directions at their adjacent ends, the one to act as an open closure for said ramping space and the other to act as a ramp for said cars and means cooperatively uniting the free ends of said sections to insure said vertical movement in opposite directions.

ALEXANDER M. McDougall.
